Primary Examiner—Martie Thompson

Attorney, Agent, or Firm—Rader, Fishman & Grauer PLLC

[57] **CLAIM**

The ornamental design for stationary kit, as shown and described.

DESCRIPTION

FIG. 1 is a perspective view of a stationery kit in an exploded condition showing my new design;
FIG. 2 is a perspective view of the scissors extended from the holder thereof;
FIG. 3 is a perspective view of the cutter extended from the holder thereof;
FIG. 4 is a perspective view of the rolling cutter extended from the holder thereof;
FIG. 5 is a perspective view of the scraper extended from the holder thereof;
FIG. 6 is an interior elevational view of the holder in an exploded condition, the implements removed for convenience of illustration;
FIG. 7 is a perspective view of the cutter extended from the holder thereof, the fragmentary ruler being shown for illustrative purposes only and forming no part of the claimed design;
FIG. 8 is a rear perspective view of the scraper element, the holder removed for convenience of illustration; and,
FIG. 9 is a perspective view of the scraper and a fragment of the cutter illustrating a portion of the cutter blade being removed.
